TRANSLATING MECHANISM

Charles R. Doty, Yonkers, N. Y., assignor to International Business Machines Corporation, New York, N. Y., a corporation of New York

Application August 25, 1939, Serial No. 291,912

6 Claims. (Cl. 178—27)

This invention relates to translating mechanisms of a type commonly used in communication systems and, more particularly, to power operated typewriters adapted for remote control.

It is the general object of the instant invention to provide an improved power operated typewriter of simple and novel construction and especially suitable for control by coded impulses sent from a distantly located transmitting station.

Among the more specific objects are speed of operation, accessibility of parts for service, flexibility of structure for varied code uses, and an improved power reamer for providing the actuating force to effect printing of characters representative of the received impulses in accordance with a preselected code.

It is proposed to provide a unit construction mountable conveniently under the well known electro-matic typewriter in such a manner that it causes the base of said typewriter to be raised only a very small increment above its normal position. The structure is thus very compact and is suited for use on any ordinary desk or table without provisions for special mountings. By simply loosening two holding screws, the entire lower unit may be swung down out of contact with the typewriter mechanism so as to provide accessibility for inspection and service as well as to permit a quick addition of this type of control unit to the ordinary typewriter.

As for the translating mechanism itself, a plurality of seeker levers are provided, and each has operating connection with a particular one of the typewriter key levers so that a downward movement imparted to any of the seeker levers causes sufficient depression of its related typewriter key to effect printing. A plurality of permutation bars are positioned in accordance with the energization of a plurality of control magnets upon reception of coded impulses, and the position of these bars determines which of the seeker levers is to be rendered effective for operation by a power driven reamer or cam shaft to cause printing of characters represented by the coded impulses.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a cross section of the typewriter showing the relationship of the various units.

Fig. 1a is a modified view of the seeker lever and cam shaft arrangement shown in Fig. 1.

Fig. 2 is a plan view of the magnets of the translating unit.

Fig. 3 is an end view of the clutch mechanism.

Fig. 4 is an enlarged plan cross section detail view of the clutch mechanism.

Fig. 5 is a detail view of the motor contacts and the devices for operating the same.

Fig. 6 is a detail view of the locking mechanism for holding the permutation bars operated for a predetermined time.

Before considering the preferred embodiment of the invention per se as shown in the drawings, a brief description of the typewriter structure alone will be given so that later, when the translating control unit is described, a better understanding may be had in regard to the cooperation between said control unit and the typewriter.

Typewriter mechanism

For illustrative purposes, this invention is shown as embodying a well known type of recording unit at the transmitting station, which may be similar in construction to the electro-matic typewriter, shown and described in detail in U. S. Patent No. 1,777,055, and hence requires only the following brief description.

Referring to the drawings and particularly to Fig. 1, well known means are provided for actuating the type bars 16, comprising a constantly rotating roller 19, cooperating with a series of individual power units each comprising a cam 11, the engagement of the cams with the roller being controlled selectively by the character key bars 17. The operating means for key bars 11 will be described later.

Any suitable means may be provided to rotate the power roller, in the direction indicated by the arrow, which is adapted to cooperate with two rows of cam units arranged in the front and rear of the roller. The cam 11 may be provided to be pivoted on one arm of a bell crank lever 12 which is pivoted in the frame of the recording unit, as indicated generally by reference character 13, the other arm of the said bell crank lever is operatively connected with an arm of bell crank lever 14 by means of link 15. Another arm of the said lever 14 is connected to the type bars 16 in a well known manner, so as to effect operation of the type bars or any other suitable means connected to the bell crank levers upon

selective operation of the controlling key bars 17.

The pivoted bell crank lever 12 is operated by the associated cam 11 whenever the latter engages the driven rollers; the engagement of the cam with the roller is controlled by means of the associated control key bar 17 in a manner which will now be briefly described.

The cams occupy normally the positions as shown in Fig. 1. In this position the impeller-arm 18 is urged, by the associated coil spring 19, against one of the impeller-lugs 29, which at the time is in the lower position, and tends to turn the cam 11 in a clockwise direction. This is prevented, however, by the engagement of one of the detents 21 on the cam, with the upper stop lug 22 on the stop lever 23. If, however, the corresponding key bar is operated, the bifurcated lower end of extension arm 24 associated with one of the said key bars 17 engages an arm 25 at the upper end of the stop lever 23 which is provided with an offset projection at its end which extends laterally through an opening in the bell crank lever 12. The arm 25 of the stop lever 23 is then swung rearwardly or to the left as viewed in Fig. 1 about the pivot 26 and its lower end forwardly or to the right as viewed in this figure, thus releasing the cam, which then turns under the influence of the spring urged impeller-arm 18. In doing so the upper serrated lobe of the cam is brought into engagement with the power roller, which turns in a counterclockwise direction and therefore causes a continued rolling movement of the cam until the high point has been reached and passed. This causes the whole cam unit to swing around the pivot 13 so as to pull down the corresponding link and actuate one of the type bars or any other mechanism with which the cam unit may be connected.

After the high point of the cam is passed, the cam loses contact with the roller, but the said impeller-arm 18 tends to continue the rotation thereof by engaging the second impeller-lug 29 of cam 11 until the second detent 27 engages one of the stop lugs. Since the half rotation of the cam consumes only a small fraction of a second, it is difficult to release the key bar within this short interval, so that it is the lower lug 28 which is first engaged, but upon the release of the key bar and the return of the stop lever 23 to normal position, this lug 28 disengages the detent, whereupon the impeller-arm rotates the cam slightly, and the said detent then engages the upper stop lug 22.

It is obvious then that depression of a key bar releases the revolubly mounted cam to engage and be actuated by the power roller in turn operating the associated bell crank lever and its attached links to cause the associated mechanism such as the type bars and other operating mechanisms to be operated. It is to be understood that an individual cam unit is provided for each type bar or other functional mechanisms associated therewith.

The action of the cam mechanism has been described with respect to one of the rear bank of cam units; in the case of those of the forward bank the operation is analogous but the directions of movement, and the order of operation of the stop lugs is reversed. For example, if the bifurcated arm 24a is positioned to engage the arm 25a at the upper end of stop lever 23a by virtue of operation of the associated key bar, the said arm is positioned rearwardly or to the left as viewed in Fig. 1, and the lower end of the

stop lever 23a is moved forwardly, that is, to the right as viewed in the said figure. This said operation is effective to release the cam, by virtue of positioning the lower stop lug 28a out of the path of detent 21a, thus permitting the spring-urged impeller-arm 18a to rotate the cam slightly in a clockwise direction to effect engagement of the lower lobe of cam 11 and power roller 10. Upon completion of a half revolution of the cam 11, the second detent 27a engages first the upper stop lug 22a while the stop lever 23a is in an operated position, but upon release of the associated key bar and the return of the said stop lever to normal position, this lug 22a disengages the said detent and the impeller-arm rotates the cam slightly so that the said detent then engages the lower stop lug 28a, as shown in the figure. In this manner the bell crank lever 12a is rotated about the pivot 13a to operate the associated type bar or any other mechanism associated therewith.

It is apparent from Fig. 1 that the movement of the above described cam unit may be utilized to operate any conveniently arranged type of transmitting mechanism such as that generally designated T. It will be noted that each operation of a typewriter cam causes its related lever L of the mechanism T to be operated so as to combinationaly position permutation bars P for operation of their individual contacts 51 for transmitting simultaneous coded impulses according to which of the typewriter key bars B have been depressed. As shown in Fig. 2, the bars P are provided with projections 52 having bevel portions 52a. These projections 52 appear on both edges of the bars P so that upon engagement of lever L with the beveled surfaces 52a, movement of the bars P to the right is effected to close contacts 51. The engaging surfaces of levers L are also beveled to the same angle to provide a large contact surface so as to reduce wear at this point to a minimum. The provision of projections 52 on both edges of the permutation bars is necessary in view of the fact that the operating levers L which are operated from typewriter cams 11 move in an opposite direction from those operated from typewriter cams 11a.

Translating control unit

A guide comb 30 has been screwed to the typewriter power mechanism frame F to keep the key bars 17 in place at that location. All key bars that are offset are arranged to be so formed in back of this comb. A stud 31 is inserted in each key bar at the point shown. These studs are approximately .060" long and form an operating connection between the key bars and a plurality of seeker levers 32 of the translating control unit. There are as many seeker levers as there are typewriter key bars and each is pivoted on a rod 33 which is held in place by seeker lever pivot support 34. The seeker levers are all biased in a counterclockwise direction about their pivots by springs 35.

A zoning reamer or cam shaft 36 is journaled in the frame F and is driven through a clutch generally designated C (Figs. 2, 4) by means of gearing 37, 38, 39 from the power roll 10. Step gearing is used so that any desired cam shaft speed may be obtained by simply changing the gear ratio.

Code bars 40 (Fig. 1) provide for selecting the proper seeker levers 32 for operation by the cam shaft 36. Five or six of these bars are sufficient

to take care of all transmission requirements. These bars are more commonly called permutation bars and will be referred to as such in the alternative from time to time. The relative positions of the permutation bars and, more particularly, the positions of the notches on these bars determine the selection of one seeker lever and the rejection of the remainder. To keep the seeker levers properly aligned in relation to the notches in the code bars a guide comb 41 is used.

A group of control magnets 42 are mounted on the angle piece 43. One of these magnets is effective upon energization to operate the clutch C, and the remainder are used to position the permutation bars. Six code bars are shown in the present embodiment and a control magnet 42 is provided for each of them. Energization of a magnet 42 by an impulse sent thereto causes armature 44 to be attracted and impart the required movement to the permutation bar with which it has mechanical connection at 45. The magnitude of movement of a permutation bar when operated by its magnet is approximately .093" under preferred operating conditions.

The translating control unit side frames 46 are mounted under the front feet 47 (Fig. 3) of the typewriter and the net result is the raising of typewriter only $\frac{1}{16}$ " above normal, allowing the complete unit to be placed as easily as the typewriter alone, without the necessity of specially constructed desks or stands. The unit pivots near the back of the typewriter on a rod 48 (Figs. 1, 2). The ends of the seeker lever support 34 are slotted and held in place by means of four screws 49. To attach the unit to the typewriter the screws are merely loosened and the support is slid to the left (see Fig. 2) as far as possible which allows the seeker levers 32 to come between the key bar studs 31 and the adjacent key bars 17. After the typewriter mounting feet are in place the support is then slid to the right so as to position the seeker levers over studs 31 on the key levers, each of the seeker levers being formed with an eye portion at the top thereof which fits conveniently over these studs. Screws 49 are then tightened to secure it in place.

Assuming a combination of impulses representing a character is sent to energize magnets 42 simultaneously in accordance with some preselected code, the operation would be as follows: Selective energization of magnets 42 by the incoming impulses causes positioning of their related permutation bars in such a manner as to allow one of the seeker levers 32 to drop into operating engagement with the contour of the cam shaft 36. The movement of any permutation bars through the medium of the bail 67 is directed to close a pair of contacts 50 causing the energization of the particular one of magnets 42 which controls the operation of clutch C. Thus, cam shaft 36 will start to turn under the same driving means which operates the typewriter power roller 10 through the gearing 31, 38, 39. Common practice has shown that this shaft should turn at a speed of between 400 and 600 R. P. M. for the most satisfactory results. The clutch is so designed that the cam shaft 36 makes one half revolution per cycle. The cam shaft is provided with two step portions 36a which are adapted to engage the seeker levers in a manner which will be explained presently.

In the normal position of the cam shaft, the seeker levers are held clear of the code bars 40 by virtue of a high portion 36b of the cam shaft

36. As the cam shaft starts to rotate all seeker levers are urged to follow the contour of the cam shaft under the biasing action of their individual springs 35 as previously described. 5 However, the inherent design of the code bars is such as to arrest the movement of all but one of the seeker levers which is permitted to follow the contour of the cam shaft down to one of the stepped portions 36a. Engagement of the 10 selected seeker lever with the step 36a causes a downward movement to be imparted to the seeker lever which is transmitted to the connected key bar 17 to cause the typewriter to print the corresponding character. When the typewriter key bar is near the end of its downward stroke, the contour of the cam shaft is such as to effect disengagement of the seeker lever from the step 36a and force it and all the others away from the permutation bars so that these bars are free to return to their normal positions for the selection of the next character.

Fig. 1a shows a modified arrangement where in the seeker lever guide comb 41 is provided with a cam portion 41a. This cam portion operates against the lower end of the selected seeker lever so as to cam it out of engagement with the step 36a of the cam shaft 36 at the proper time. Inasmuch as the mechanism is designed to function in response to short simultaneous coded impulses, as is evident from the description of the transmitting mechanism, some means is required for maintaining the code bars in their energized positions for a sufficiently long period to permit analysis by the seeker levers as previously described. Such a locking means is shown in Figs. 5, 6. When any code bar 40 becomes energized, its movement to the right is sufficient to cause projection 53 to engage lower portion 51 of bail 54 forcing it to pivot to the right so as to allow locking lever 55 to fall off latch point 61 of bail 54 and assume a position on either side of a projection 53 which is common to all the code bars thereby locking all the bars in either energized or normal positions. The code bars are thus locked until after the analyzing operation has been performed at which time lever 55 is forced out of engagement with the code bars by a cam 60 on cam shaft 36 an amount sufficient to allow the code bars to return to normal and 50 allow latch point 61 on bail 54 to assume the position shown in Fig. 5 which is effective to hold lever 55 in its latched position after it is released by cam 60. The travel of code bars 40 in either direction is limited by a stop plate 62 which projects up into a recess 40a provided in each of the code bars.

In order to insure the positive return of the code bars, a knock-off bail 63 is arranged to be operated near the end of the cycle by a cam 65 (Fig. 2) which is also fixed to the end of cam shaft 36. A spring 64 causes the knock-off bail to follow the contour of the cam 65.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. Translating apparatus of the class described comprising, in combination, a plurality of control

magnets, permutation bars adjacent said magnets and positionable thereby, a plurality of character selection levers, a plurality of seeker arms having pin and slot connections with said character elements and coacting with the permutation bars so as to render one of the seeker levers operative and the remainder inoperative upon positioning of the bars by the magnets, and a cyclically operating stepped cam for engaging the seeker lever in operative position to impart movement thereto in one direction to effect printing and to move said seeker lever in a transverse direction to release it from the cam at a predetermined time in the cycle.

2. Translating apparatus of the class described comprising, in combination, a plurality of control magnets, code bars adjacent said magnets and positionable thereby, a rotating cam member having stepped portions and cam portions around its contour, a plurality of character key bars, operating arms having pin and slot connections with said key bars at one end and being biased toward said cam member at the other end, all except one of said arms being restrained by the code bars from engagement with a stepped portion of said cam member, and said one arm upon engagement being moved in one direction by the stepped portion to operate the related character key bar to effect printing and in another direction by the adjacent cam portion to release the arm to cause the character key bar to be restored to normal.

3. Apparatus of the class described comprising character selection elements and power means for operating the same, individual operating means interconnecting said power means with said elements having pin and slot connections with the elements and being biased toward engagement with the power means, permutation means including code bars normally restraining said individual operating means from engagement with said power means, a plurality of control magnets for positioning said code bars so that one of the operating means is operated by the power means, a supporting means for said operating means adapted to be manually shifted to a limited extent sufficient to break the pin and slot connections between the character selection elements and their individual operating means to permit all of the individual operating means to be removed together as a unit.

4. Apparatus of the class described comprising, character selection elements and power means for operating the same, individual seeker arms

interconnecting said power means with said elements having pin and slot connections with the elements and being biased toward engagement with the power means, permutation means including code bars normally restraining the seeker arms away from said power means, a plurality of control magnets for positioning said code bars so that one of said bars is operated by the power means, and a common pivotal support for all of seeker arms adapted for limited movement manually to the side sufficient to permit all of said arms to clear the pins of the character selection bars so that the arms and their support may be removed together as a unit.

5. A control unit attachment for a power driven typewriter pivotally mounted at one end and fastened securely to the typewriter at the other comprising, in combination, a plurality of character key bars each having a connecting pin projecting from them substantially at the perpendicular, a plurality of seeker levers having eyes at the top thereof adapted to fit over said pins in such a way as to allow normal operation of the typewriter, permutation means for determining which of said levers is to become operative to be engaged by the power drive of the typewriter in accordance with a preselected code, and a supporting member for said seeker levers adapted to be shifted to one side upon unfastening the same to provide for the removal of all of said seeker levers together by simply swinging the control unit about its pivot in a direction away from the typewriter.

6. Apparatus of the class described comprising character selection elements and power driven means for operating the same, individual seeker arms interconnecting said power driven means with said elements having operating connection with said elements and being biased toward engagement with the power means, permutation means including a plurality of code bars normally restraining the seeker arms away from said power means, electromagnetic means for positioning said bars according to a preselected character code so that one of the seeker levers is permitted to move into engagement with the power means, and a clutching device responsive to the movement of any one of said code bars for rendering the power driven means effective to operate the engaged seeker lever to operate the character selection elements for the purpose of recording the character.

CHARLES R. DOTY.
